METHOD OF MAKING GAS.

1,166,183.

Specification of Letters Patent. Patented Dec. 28, 1915.

Application filed June 1, 1914. Serial No. 841,988.

To all whom it may concern:

Be it known that I, HENRY A. CARPENTER, a citizen of the United States, residing at Sewickley, in the county of Allegheny and 5 State of Pennsylvania, have invented certain new and useful Improvements in Methods of Making Gas, of which the following is a specification.

My invention relates to the manufacture 10 of gas, and more particularly to the manufacture of coal-gas by the distillation of coal placed within the retorts of a gas-bench, and distilled therein by the employment of gas generated in a gas producer connected 15 with the bench.

In the operation of apparatus of the class mentioned as heretofore practised, considerable trouble has arisen by reason of the combustion gas, that is to say, the gas employed 20 for heating the retorts, mixing with the retort or illuminating gas. This mixing is caused either by an excess of pressure within the retorts causing the gas therein to leak through the walls of the retort and mix with 25 the combustion gas, or, on the other hand, by an excess of pressure in the combustion chamber which forces producer gas into the retorts. Heretofore, considerable pressure has accumulated in the combustion chamber, 30 particularly in the upper portion thereof, the pressure at times being considerably in excess of the pressure within the retorts.

Apparatus of the character above outlined as heretofore commercially constructed, may be divided into two classes. The apparatus of the first class includes a comparatively low gas bench of not more than three, or at the greatest four, retorts high, and in which the illuminating or retort gas is taken off from the respective retorts by means of individual pipes in direct communication with the respective retorts of the gas bench, said pipes having considerable length and of rather small cross-sectional area.

In the operation of the apparatus of the first class, the pressure in a retort immediately after the retort has been freshly charged and at which time the make of gas 50 is very rapid, is considerably increased, being higher than the average pressure during the distillation periods. This increase of pressure within the freshly charged retorts tends to force some of the gas out 55 through the walls of the retorts and by de-

positing carbon thereon closes the cracks, thus having a tendency to prevent leakage of the combustion gas into the retorts even though the pressure on the outside of the retorts is somewhat greater than the pressure 60 within.

In the apparatus of the second class, the gas bench is built high and contains as many as eight to ten superposed retorts. This apparatus of the second class is also distinguished from the apparatus of the first class in that the gas is discharged from the retorts in such a manner as to prevent any considerable rise in pressure over the desired operating pressure, even at the time the retort is freshly charged, so that the rise of pressure within the retort or retorts will not be sufficient to force the gas through the retort walls into the combustion chamber and deposit carbon in the cracks, the consequence 70 being that should the pressure within the combustion chamber or on the outside of the retorts become greater than the pressure within the retorts, the combustion gas will leak through and mix with the illuminating 75 or retort gas.

My invention particularly relates to the operation of apparatus under the second class, and the prime object is to provide a new and improved method of operating gas 80 generating apparatus whereby the mingling 85 or mixing of the retort and combustion gases is prevented.

A further object is to provide a method of operating whereby the pressure in the retort chamber, combustion chamber or space surrounding the retorts may be maintained at all times below retort pressure, with the pressure within each retort maintained substantially constant and preferably, though 95 not necessarily, below atmospheric pressure.

The gas pressure in the combustion chamber is greatest in the upper portion thereof so that the higher the retorts the greater the external pressure thereon. The approximate difference in pressure between retorts spaced twenty-five inches from center to center is .035 inches water gage. It is my purpose to preferably maintain an external pressure on the topmost retort of at least .1 100 inch water gage below atmosphere, although I do not confine myself thereto.

A further object of the invention is to operate the plant under the pressure conditions stated relatively to the combustion 110

chamber and the retorts, and at the same time regulate the pressure within the producer.

Coal gas generating apparatus suitable for practising the invention is shown diagrammatically in the accompanying drawing.

In the drawing, 1 designates a gas producer of the usual or any preferred type, 2 a retort chamber, and 3 a recuperator structure interposed between the retort chamber and the producer. Gas generated in the producer is conveyed to the combustion chamber 4 of the retort chamber through a flue or passage 5. As is usual, the gas from the producer is mixed with secondary air introduced through openings 5^a, and the combustion gas passed up through the retort chamber and around the retorts 6 therein for the purpose of distilling the coal within the retorts. For the purpose of regulating the pressure within the gas-producer and particularly for maintaining a level gage on the top thereof, I provide a valve 7.

As illustrated, the primary air for supporting combustion in the producer is forced thereto through a flue 8 by means of a blower 9. The coal gas from the retorts 6 is discharged into large stand-pipes 10 disposed in contact with or in close proximity to the retort mouth-pieces 11. Said mouth-pieces are each provided with an opening 12 through which the gas enters the stand-pipe. As illustrated, the retort gas is led upwardly by means of the stand-pipes into a main or chamber 13. 14 designates a conduit in communication with the main 13 at one end and with a pipe 15 at its other end, said pipe 15 being in turn connected with an exhauster 16 designed to draw or suck the gas from the retorts and pass it along through the system as is usual in apparatus of this character.

The products of combustion are withdrawn from chamber 2 downwardly through flues or passages 17, 18 by means of an exhauster 19 in communication with an enlarged conduit 20, the latter being connected with the passage 18 by means of a connection 21.

The method of operating the apparatus shown is as follows: The producer is supplied with a bed of ignited fuel in the usual manner, and by means of the fan or blower 9 and the exhauster 19, a current is established through the producer, etc., the air forced through the flue or passage 8 by the blower 9 reacting with the incandescent fuel and forming producer gas in the usual and well known manner. This producer gas is then passed to the combustion chamber 4 of the retort chamber where it is mixed with secondary air and utilized for heating the retorts 6. Under the action of the exhauster 19, after passing upwardly

through the retort chamber the products are drawn down into flues or passages 17, 18 into the enlarged conduit 20. In practice, the exhauster 19 is capable of and is operated in such a manner as to at all times 70 maintain a pressure throughout the interior of the retort chamber lower than retort pressure and preferably below atmospheric pressure. It will, of course, be evident that the pressure within the retort chamber will 75 not be the same throughout its height, being somewhat less near the bottom thereof than near the top. It is my preference, however, to maintain the pressure even at the top of the retort chamber below atmospheric 80 pressure and always below the pressure within the highest retort of the bench.

As here illustrated, the gas from the retorts is drawn into the stand-pipe by means of the exhauster 16, and preferably in such 85 a manner as to maintain the pressure within the retorts below atmospheric pressure, but at the same time to maintain the pressure within a given retort greater than the pressure at the exterior thereof. In other 90 words, the pressure immediately surrounding each retort will be maintained below the pressure within the retort. By this means the passage of producer gas and products through any cracks in the retort 95 walls (formed of refractory material in the usual manner) is prevented. The higher pressure within the retorts has the effect of forcing carbon into and sealing any cracks that may exist, preventing the escape of retort gas into the bench.

When, as illustrated, I employ a combined forced draft and suction operated producer in connection with my method of pressure regulation for the retort chamber and the 105 retorts therein, I am enabled to control the pressure conditions within the producer and, for example, maintain a level gage on the top of the producer.

What I claim is:—

1. In the manufacture of coal gas, the method herein described consisting in placing coal in a retort having walls through which gas may pass, subjecting the retort to coal-carbonizing temperature, and maintaining predetermined pressures at the interior and exterior of the retort.

2. In the manufacture of coal gas, the method herein described consisting in placing coal in a retort having walls through which gas may pass, heating the retort within a chamber to coal carbonizing temperature by burning gaseous fuel within such chamber, and maintaining predetermined pressures within the combustion chamber and within the retort with the retort pressure exceeding the combustion chamber pressure.

3. In the manufacture of coal gas, the method herein described consisting in plac-

ing coal in a retort having walls through which gas may pass, subjecting the retort to coal-carbonizing temperature and to predetermined external pressure, and maintaining substantially uniform pressure within the retort with such retort pressure in excess of said external pressure.

4. In the manufacture of coal gas, the method herein described consisting in placing coal in a retort having walls through which gas may pass, heating the retort within a chamber to coal-carbonizing temperature by burning gaseous fuel within such chamber, maintaining a pressure within the chamber below atmospheric pressure, and maintaining a higher pressure within the retort.

5. In the manufacture of coal gas, the method herein described consisting in placing coal within a retort having walls through which gas may pass, heating the retort within a chamber to coal-carbonizing temperature, and maintaining different pressure conditions in the chamber and in the retort with the retort pressure higher than the chamber pressure.

6. In the manufacture of coal gas, the method herein described consisting in placing coal within a retort having walls through which gas may pass, heating the retort within a chamber to coal-carbonizing temperature by burning gaseous fuel within such chamber, rarifying the gaseous fuel and products within the chamber, and maintaining a higher but substantially uniform pressure within the retort.

7. In the manufacture of coal gas, the method herein described consisting in placing coal within a plurality of retorts having walls through which gas may pass, heating all of the retorts within a chamber by burn-

ing gaseous fuel within such chamber, rarifying the gaseous fuel and products within the chamber and thereby subjecting the exterior of all the retorts to less than atmospheric pressure, and maintaining a substantially uniform pressure within all the retorts with such pressure higher than said chamber pressure.

8. In the manufacture of coal gas, the method herein described consisting in placing coal within a plurality of retorts having walls through which gas may pass, heating all the retorts within a chamber to coal-carbonizing temperature, maintaining the interior of the chamber under suction, maintaining communication between the retorts and an offtake common to all of the retorts, and maintaining the offtake under suction.

9. In the manufacture of coal gas, the method herein described consisting in placing coal within a retort having walls through which gas may pass with the retort located in a chamber, maintaining communication between the chamber and the gas outlet of a gas producer, maintaining the chamber under suction and thereby drawing the gas thereinto from the producer, burning the gas and thereby heating the retort to coal-carbonizing temperature, and maintaining a substantially uniform pressure within the retort throughout the carbonization period with said pressure higher than the pressure within the retort confining chamber.

In testimony whereof I affix my signature in presence of two witnesses.
